UNITED STATES PATENT OFFICE.

HENRY CATE ATKINSON, OF FRANKLIN, KENTUCKY.

LAMP.

SPECIFICATION forming part of Letters Patent No. 284,796, dated September 11, 1883.

Application filed July 14, 1883. (No model.)

To all whom it may concern:

Be it known that I, HENRY C. ATKINSON, a citizen of the United States, and a resident of Franklin, in the county of Simpson and State 5 of Kentucky, have invented certain new and useful Improvements in Lamps; and I do hereby declare that the following is a full, clear, and exact description of the invention, which will enable others skilled in the art to which 10 it appertains to make and use the same, reference being had to the accompanying drawings, which form a part of this specification, and in which—

Figure 1 is a perspective view of my improved lamp. Fig. 2 is a vertical sectional view of the same. Fig. 3 is a detail view, showing the inside with the oil-guard; and Fig. 4 is a plan of the reflector-blank before bending it into shape to form the reflector.

20 Similar letters of reference indicate corresponding parts in all the figures.

My invention has relation to lamps adapted for kitchen and general household use; and it consists in the detailed construction of a reflector-lamp of that class, as hereinafter more 25 fully described and claimed.

In the accompanying drawings, A is the oil-reservoir of my improved lamp, which is struck up from sheet metal of circular shape 30 and made slightly tapering, so as to form a large base, B. To the lower rim of this base is secured the semi-cylindrical reflector C, which extends up to some distance above the top of the burner, where it is provided with 35 the reflector-hood D, formed by bending the rounded top part of the blank, which is provided with triangular slots or notches E, down across the middle line, F, and soldering the sides of the notches E together along their 40 edges, thereby causing the reflector-hood to be bent inwardly against the chimney of the lamp, as will appear more clearly by reference

to Fig. 2 of the drawings. The back part of the reflector is provided with a handle, G, on the top of which is a ring, H, whereby the 45 lamp may be suspended from a hook on the wall, the handle being made flat, so as to form a firm bearing-surface against the wall and cause the lamp to hang steady when so suspended. The reservoir is provided with a 50 threaded inlet-tube, I, which is closed by a screw-cap, J, of the usual construction. Immediately underneath the inlet-tube is placed the oil-guard K, which consists of a plate soldered on both sides to the top of the reservoir, 55 and extending inwardly to the wick, its inner end being narrowed, as shown at L in the detail view, Fig. 3.

In filling the reservoir with oil, this runs 60 back to the wick and then into the reservoir through the narrow part or channel L of the guard, and if in carrying the lamp it should be slightly tilted the oil will be prevented from entering the inlet-tube by the oil-guard K, so no oil can leak by capillary action between the threaded inlet-tube I and its screw-cap J.

Having thus described my invention; I claim and desire to secure by Letters Patent of the United States—

As an improvement in lamps, the oil-reservoir A, having threaded inlet-tube I and screw-cap J, and provided with the oil-guard K, fastened to the top of the reservoir, and extending inwardly to and narrowed in the direction of the wick, substantially as and for the purpose shown and set forth.

In testimony that I claim the foregoing as my own I have hereunto affixed my signature in presence of two witnesses.

HENRY CATE ATKINSON.
